US00D991798S

(12) **United States Design Patent** (10) **Patent No.:** **US D991,798 S**
(45) **Date of Patent:** **** Jul. 11, 2023**

(54) **METAL DETECTOR**

(71) Applicant: **Shenzhen Yishifu Technology Innovation Co., Ltd.**, Shenzhen (CN)

(72) Inventor: **Qing Shi**, Shenzhen (CN)

(73) Assignee: **Shenzhen Yishifu Technology Innovation Co., Ltd.**, Shenzhen (CN)

(**) Term: **15 Years**

(21) Appl. No.: **29/814,749**

(22) Filed: **Nov. 9, 2021**

(30) **Foreign Application Priority Data**

Oct. 29, 2021 (CN) 202130712013.2

(51) **LOC (14) Cl.** **10-04**

(52) **U.S. Cl.**
USPC **D10/47**

(57) **CLAIM**

The ornamental design for a metal detector, as shown and described.

DESCRIPTION

FIG. 1 is front perspective view of a metal detector showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 2; and,

FIG. 10 is a partial enlarged view of FIG. 2.

The broken lines depict portions of the metal detector and form no part of the claimed design.
